UNITED STATES PATENT OFFICE.

EDWARD TROST, OF JACKSONVILLE, FLORIDA.

ESCAPEMENT MECHANISM.

1,416,528.

Specification of Letters Patent. Patented May 16, 1922.

Application filed February 10, 1920. Serial No. 357,496.

To all whom it may concern:

Be it known that EDWARD TROST, a citizen of the United States of America, residing at Jacksonville, in the county of Duval 5 and State of Florida, has invented new and useful Improvements in Escapement Mechanism, of which the following is a specification.

The object of the invention is to provide 10 an efficient escapement mechanism especially adapted for watches and clocks of the balance-wheel type whereby an accuracy of vibration and uniformity of timing function may be secured with the minimum possibility 15 of disarrangement of the elements due to jarring or other outside influences, and with this object in view the invention consists in a construction and combination of parts of which a preferred embodiment is shown in 20 the accompanying drawings, wherein:

Figure 1 is a front view of the mechanism.
Figure 2 is a side view of the same.

Figure 3 is a sectional view on the plane indicated by the line 3—3 of Figure 2.
25 Figure 4 is a detail view of the safety roller and table.

Figure 5 is a similar view of the escapement lever.

Figure 6 is a similar view of the escapement fork.

The mechanism consists essentially of the escapement lever 10 fulcrumed at 11 with its arms 12 in operative relation with the teeth of the escapement wheel 13, and a roller table 35 14 carrying a safety roller 15 and provided with an impulse pin 16 in operative relation with an escapement fork 17, said roller table being carried by the balance staff 18 to which may be attached the usual balance 40 wheel 19 and balance spring 20. The escapement fork which is carried by the upper extremity of the escapement lever consists of the inwardly divergent prongs 21 shown clearly in Figure 3 and the impulse pin 16 45 is preferably of cross-sectionally triangular form for alternate knife edge contact with the annular preferably convexed surfaces of the prongs under the impulse derived from the balance spring acting through the balance staff and roller table, while the yoke 22 50 of the escapement lever which operates in the plane of and spans the safety roller 15

is provided with a safety pin 23 for peripherally traversing the safety roller through a notch or cut-away portion 24 therein. The 55 path of movement of the escapement fork is shown by the dotted line 25 in Figures 1 and 3 while the direction of movement of the impulse pin is shown by the dotted line 26 in Figure 3, it being obvious that the safety pin 23 in traversing the safety roller passes at each vibration through the notch or cut-out portion of the safety roller which is disposed in a position to prevent an excessive movement of the escapement lever.

The disposition of the safety roller 15 in the plane of the escapement lever 10 makes for a construction relieving the latter of any torsional or twisting strain in the event that the safety pin impinges on the periphery of 70 the safety roller, as might occur in the event of a too great stroke being imparted to the escapement lever. The arrangement provides for the resumption of the normal position of the parts without any tendency to 75 twist the escapement lever with resultant probable damage to either the fork or the impulse pin. Were the safety roller, as is usual, disposed in some other plane than that of the lever, any engagement of the safety 80 pin 23 with the periphery of the roller would tend, because of the point of strain being offset from the point of resistance (which is the pivot point 11) to create the torsional or twisting strain of the lever above referred to.

What is claimed is:

1. An escapement mechanism having in combination with the balance staff and escapement wheel, an escapement lever provided at its free end with a fork and having an intermediate yoke, a roller table carried by the balance staff and having an impulse pin for engagement by said fork, a safety roller carried by the balance staff in the plane of the yoke of the escapement lever, and a safety pin carried by the escapement lever for traversing a safety notch in the said roller.

2. An escapement mechanism having in combination with the balance staff and an escapement wheel, an escapement lever provided at its free end with a fork having inwardly divergent prongs, a roller table carried by the balance staff and having an im-

pulse pin presenting knife edge contacts for engagement respectively with the prongs of the fork, said escapement lever having an intermediate yoke spanning the balance staff, a safety roller carried by the balance

5 staff in the plane of the escapement lever and embraced by the yoke thereof, and a

safety pin carried by the escapement lever in traversing relation with a safety notch in said roller.

10

In testimony whereof he affixes his signature.

EDWARD TROST.
